UNITED STATES PATENT OFFICE.

WALTER O. LUM, OF PITTSBURGH, PENNSYLVANIA, ASSIGNOR TO WESTINGHOUSE ELECTRIC AND MANUFACTURING COMPANY, A CORPORATION OF PENNSYLVANIA.

SWITCHING MECHANISM.

1,370,028.

Specification of Letters Patent.

Patented Mar. 1, 1921.

Application filed May 27, 1916. Serial No. 100,370.

To all whom it may concern:

Be it known that I, WALTER O. LUM, a citizen of the United States, and a resident of Pittsburgh, in the county of Allegheny and State of Pennsylvania, have invented 5 a new and useful Improvement in Switching Mechanisms, of which the following is a specification.

My invention relates to switching mechanisms and it has for its object to provide an 10 arrangement that is simple in construction and compact in form.

According to the present invention, the removable parts of the switching mechanism 15 are punched from plates of metal. The supporting members are mounted upon, and insulated from, an operating shaft. The movable contact members, which are pivotally mounted upon the supporting 20 members, are provided with semi-circular bearing faces in order that the movable contact members may be readily removed for the purpose of inspection or repair. The movable contact members, which are disposed in pairs, are retained in position by suitable springs and stop devices consisting of a stationary member and projecting arms connected to each of the switch members. The stationary parts of the switching 25 mechanism are made of straps which are bent to conform to the shape of the supporting bars and are provided with integral projections punched out and bent to rigidly clamp the movable members to their respective supporting members.

In the accompanying drawings, Figure 1. is an end view, partially in elevation and 30 partially in section, of a switching mechanism constructed in accordance with my invention. Fig. 2 is a side view, partially in elevation and partially in section, of the mechanism of Fig. 1.

A switching mechanism 1 comprises a movable portion 2, and stationary portions 45 3 and 4. The movable portion 2 comprises a pivotally mounted polygonal shaft 5 that is provided with a sleeve 6 of insulating material.

Mounted upon the shaft 5 and clamping 50 the sleeve 6 are a series of members 7 that serve to support movable contact members 8. The members 7 are provided, at their upper portion, with slits 9 in order that the members 7 may be rigidly clamped to the 55 insulated shaft 5 by means of bolts 10. The

bolts 10 constitute terminal members for the contact members 8. The contact members 8 are secured to members 11 having substantially semi-circular bearing surfaces 12 and projecting portions 13 which coat 60 with a stationary stop pin 14.

The members 13 may be electrically connected to the terminals of the line conductors. The members 11 are normally held outwardly with the bearing surfaces 12 65 against their coating pivotal supports 15 by means of springs 16. The shaft 5 is provided with an operating handle 17.

Each of the stationary portions 3 consist of a supporting rod 18 that is surrounded 70 by a sleeve 19 of insulating material and a series of members 20 which are formed of straps of metal bent to conform to the exterior of the sleeve 19. Each of the members 20 is provided with integral projections or tongues 21 which are punched from the sides of the members 20 and are bent inwardly to rigidly clamp the members 20 in position. Each of the members 20 is provided with contact members 22 for coating 75 80 with the corresponding movable contact members 8.

The sides of the members 20 are clamped against the sides of the sleeve 19 by bolts 23 which also constitute terminal members 85 for the stationary contact members 22.

In the operation of the switching mechanism as, for example, in starting an electric motor, the operating handle 17 is actuated 90 in either direction from its neutral or inoperative position to the starting position. It may be assumed that the shaft 5 and its connected parts are rotated in a counter-clockwise direction, as viewed in Fig. 1. The contact members 8, on the right, engage 95 their corresponding stationary contact members 22 to close the circuits controlled by them.

The contact members 8 are yieldingly held in engagement with the corresponding 100 contact members 22 by means of the springs 16 which have been compressed by the rotation of the members 11 about their respective pivots.

When the motor, or other device controlled by the switching mechanism, has 105 reached a desired speed, the handle 17 is actuated quickly to its running position in order to effect a quick separation of the contact members for closing the starting cir- 110

cuits and for effecting a quick engagement of the contact members for completing the running circuits of the motor.

The springs 16 are again compressed by the rotation of the members 11, on the left, about their points of pivotal support, the members 11 on the right constituting a support for the spring since they are prevented from rotating by the projections 13 and the 10 coacting stop pins 14.

When the handle 17 and its connected parts are returned to their respective inoperative positions, the members 11 are turned to their illustrated positions with the projections 13 in engagement with the pins 14.

The various parts of the switching mechanism described above may be manufactured with a minimum expenditure of time and labor in view of the fact that they may, for 20 the most part, be formed by a single operation; for example, the members 7, 11 and 20 may be punched from plates or straps, as the case may be, of sheet material. The various parts may be readily assembled and 25 secured in position. In order to place the members 11 and the attached contact members 8 in their operative positions, it is only necessary to compress the spring 16 to such degree that the members 11 may be inserted 30 between the members 15.

The switching mechanism constituting the subject-matter of the present invention is particularly adapted for use in connection with automatic starters for electric motors 35 but it will be understood that it may be employed in any mechanism of a similar character which embodies corresponding parts.

I claim as my invention:

1. In a switching mechanism, the combination 40 with a plurality of pivotal supporting members and a corresponding number of members having substantially semi-circular

bearing portions for coacting with said pivotal members, of means for yieldingly maintaining the operative relation of said members and said portions. 45

2. In a switching mechanism, the combination with a plurality of pivotal members and a corresponding number of members having substantially semi-circular bearing portions for coacting with said pivotal members, of means tending to rotate said last named members in opposite directions and means for limiting such rotative movements. 50

3. In a switching mechanism, the combination with a supporting member, and a plurality of members pivotally mounted thereon and having substantially semi-circular bearing surfaces, the open sides of which 60 are oppositely disposed, a stop for limiting the rotative movement of said pivotally mounted members, and a spring for retaining said pivotally mounted members in operative relation to said supporting member. 65

4. The combination with a pair of stationary contact elements, of a pair of co-operating movable contact elements normally occupying an inoperative position, means for maintaining said movable elements separated, means for limiting the degree of separation of said movable elements and means for actuating one of said movable elements into engagement with the corresponding stationary element, said other element then serving as a support for said maintaining means to cause said maintaining means to effect firm engagement between said one movable element and said corresponding stationary element. 70 75

In testimony whereof, I have hereunto subscribed my name this 11th day of May 1916.

WALTER O. LUM.
